UNITED STATES PATENT OFFICE.

FREDERICK M. STEVENS, OF BROOKLYN, NEW YORK.

PATTERN FOR CASTING.

SPECIFICATION forming part of Letters Patent No. 380,827, dated April 10, 1888.

Application filed July 25, 1887. Serial No. 245,238. (No model.)

To all whom it may concern:

Be it known that I, FREDERICK M. STEVENS, of Brooklyn, New York, have invented certain new and useful Improvements in Patterns for Castings; and I do hereby declare the following to be a full, clear, and exact description of my invention, which will enable others skilled in the art to which it appertains to make and use the same.

10 My invention relates to a new and improved means of casting metal about tapped nuts, whereby the nut may be automatically located in the mold and accurately held in position there during the operation of casting without 15 the use of supplementary holding devices.

The object of my invention is to produce in manufactures of cast metal, without the labor or expense of drilling and tapping and without the use of supplementary holding devices, 20 screw-holes which shall be uniform in size and have such absolute accuracy of position and place as to be exactly in line with the hole drilled or cast in any one of a number of duplicate corresponding parts of the manufacture.

25 In the case of many manufactures made wholly or partly of cast metal the pieces are held together by screws passing through one piece and screwed into a hole drilled and tapped in the other piece after casting. A sa-

30 milar example is the case of hot-air and ventilating registers, where the perforated face is usually fastened to the frame in this manner. The frame is cast with lugs at the corners or elsewhere, and these lugs are drilled and tapped

35 to correspond with holes cast in the face of the register. Three distinct operations are thus made necessary in the lugs—the casting, the drilling, and the tapping. Where this method of producing the screw-holes is employed it is

40 practically difficult to locate the screw-hole so as to be in line with the hole drilled or cast in the corresponding part of the register or other manufacture, and a slight deviation in the position of the screw-hole in the lug will make it

45 impossible to screw the parts together. An additional disadvantage is that iron is liable to come out so hard in casting that the lug cannot be drilled or tapped and the casting is useless. Attempts have been heretofore made

50 to obviate these difficulties by introducing a nut into the mold and securing it by casting other parts around it; but in all these attempts

either the nut has been introduced into the mold after the pattern is drawn, in which case it is impossible to locate the hole accurately, or 55 else some supplementary device—such as a mandrel or stud—has been employed to hold the nut in place in the pattern or the mold.

I am also aware that attempts have heretofore been made to introduce previously-prepared parts of a metallic structure into a mold by inserting the parts in the pattern; but in these attempts, also, a hood or some other supplementary device for holding the previously-prepared part has been employed. This supplementary device has to be removed after the casting is made, and the operation is thus rendered both more complicated and more expensive.

50 My invention does away with any supplementary holding device, the nut being supported in the mold solely by the sand. At the same time the screw-hole is located accurately and automatically.

55 In order to explain my invention I make the following detailed description, reference being had to the accompanying drawings, which are hereby made a part of this specification.

60 In the figures similar letters refer to similar parts.

65 Figure 1 is a front elevation of so much of the face and frame of a hot-air register as will show the application of my invention. Fig. 2 is a cross-section of Fig. 1 through 2 2. Fig. 3 is a view of the pattern P, with nuts E E in 85 place in the lugs D D, prior to molding. Fig. 4 is a vertical section of the flask, showing the pattern in the sand and the nuts in the pattern. Fig. 5 is a vertical section of the flask and mold after the pattern is drawn, the nuts 90 remaining in the sand. Fig. 6 is a cross-section of Fig. 4 through line 6 6.

70 A is the side of the register.

B is the end piece.

C is the lug.

75 The inclosed nut appears at E E.

To carry out my invention in its preferred form I take a tappet-nut, E, of iron or other metal and of any desired size. On the pattern P, from which the mold is to be made, 80 which pattern may be of any suitable material, I construct a forked lug, D, having branches d d, and groove the inner face of each branch to fit the nut at c c, the branches being of such

size as when grooved to allow metal enough to give the required strength about the nut. The branches *d d* are at such a distance apart and of such a size as loosely to receive and hold 5 the nut *E*, which just slides into and out of the grooves *c c* easily, and at the same time to leave the hole *G* and a part of each side of the nut *E* at *K K* exposed. The nuts being placed in position in the pattern, when the operation 10 of molding is gone through with, the sand will be packed on each side of the nut *E* at *K K* and through the hole *G*. When the pattern is drawn, the nut *E* will be left in its correct position in the mold, and will be held accurately 15 in place until the casting is complete merely by frictional contact with the sand without any supplementary holding device. The sand will prevent the hot metal from entering the screw-hole *G*, while at the same time the nut 20 *E* will become securely integral with the finished casting. When the casting is completed, the hole *G* will be exactly in position to receive the screw *F*. All necessity for a hood or other supplementary holding device is thus

done away with. The correct position in the 25 casting for the hole *G* being once determined, the position is fixed by constructing the forked lug on the pattern so as to hold the nut at just the proper point. Then the hole *G* will appear in its proper position in the casting with 30 absolute and unvarying accuracy.

The mold-box is shown at *X*, the bottom board at *X'*.

I do not claim, broadly, securing a nut in a metallic structure by introducing the nut into 35 a mold and casting other parts about the nut; but

What I do claim as new, and desire to secure by Letters Patent, is—

The pattern *P*, having forked lug *D* projecting from its face, said lug having branches *d d* grooved internally at *c c* to fit a tappet-nut, *E*, substantially as shown and described, and for the purposes set forth.

FREDERICK M. STEVENS.
